TROLLEY HANGER

Filed Dec. 8, 1922

UNITED STATES PATENT OFFICE.

FRANK CHESZNEKY, OF YUKON, WEST VIRGINIA.

TROLLEY HANGER.

Application filed December 8, 1922. Serial No. 605,577.

To all whom it may concern:

Be it known that I, FRANK CHESZNEKY, a citizen of Hungary, residing at Yukon, in the county of McDowell and State of West Virginia, have invented certain new and useful Improvements in Trolley Hangers, of which the following is a specification.

This invention relates to trolley wire supports or hangers, having for an object to provide a simple and efficient form of hanger which can be readily attached to and detached from the trolley wire and which will securely grip the latter.

For further comprehension of the invention, and of the objects and advantages thereof, reference will be had to the following description and accompanying drawings, and to the appended claims in which the various novel features of the invention are more particularly set forth.

Fig. 1 of the drawings is a side view of one form of my trolley wire hanger, showing a portion of a trolley wire attached thereto.

Fig. 2 is an elevation at right angles to Fig. 1.

Fig. 3 is a side elevation, partly in vertical section, showing another form of the invention.

Fig. 4 is an elevational view, partly in vertical section, at right angles to Fig. 3.

Fig. 5 is a detail perspective view of the supplementary clamping element shown in Figs. 1 and 2.

In the drawings I have indicated at 10 a trolley wire drawn to form a groove or channel 11 extending along each side thereof. Engaging in these grooves are lips 12 formed on the lower edges of a pair of clamping plates 13 and 14 respectively. These plates have formed integral with their upper edges the similar semi-cylindrical projections 15 and 16 the flat faces of which register with one another, while the rounded faces are screw-threaded, the threads on the two projections registering with one another, these two members 15, 16 forming, in effect, when laid face to face a single screw-threaded stud.

As shown in the drawings the projections 15, 16 are transversely offset, with relation to their respective plates and the projection is passed through an aperture in the plate thus interlocking the two plates together.

The stud 15, 16 is threaded onto a coupling

collar 17 suitably swiveled on a head 18 provided with lugs 19 whereby it is pivotally connected as at 20 to the lower end of a supporting pole 21. To cause the lips 12 to grip the wire 10 when the coupling 17 is screwed over the stud 15, 16 a pair of co-operating fulcrum ribs 15^a, 16^a are formed on the lower ends of the stud elements 15, 16.

In Figs. 3 to 5 I have shown a modified construction comprising wire gripping plates 13', 14' having integral parti-screw extensions 15', 16' which when laid together form a single screw. Engaged with this screw is a barrel 25 rotatably and slidably held on a spool-like member 26 having flanges 28 on opposite ends thereof, the barrel 25 having an interior recess 27 formed by enlarging its bore in which the forward flange 28 engages. The member 26 is provided with lugs 29 whereby it is pivotally attached to the pole 21.

A ring 30 is placed freely over the stud 15', 16' and is provided with a pair of downwardly projecting legs 31 having V-notches 32 in their lower ends whereby they may straddle and press together the plates 13', 14' adjacent the gripping edges of the latter.

With this modified form of hanger accurate fitting of the threads on the barrel 27 and the two-part stud is not needed as the notched ends of the legs 31 force the plates 13', 14' into gripping contact with the wire 10.

Having thus described my invention what I claim as new and desire to protect by Letters Patent of the United States is as follows:

1. A trolley wire support comprising a pair of vertical plates adapted to grip the sides of the wire and formed with semi-cylindrical screw-threaded upward extensions jointly forming a stud, said extensions being transversely offset from their respective plates, one of them extending through an aperture in the other, abutting fulcrum ribs formed on adjacent faces of said extensions, and a member screwed on said extensions, and a device adapted to be pressed downwardly by said member to press said plates against the wire.

2. A trolley wire support comprising a pair of vertical plates adapted to grip the sides of the wire and formed with semi-cylindrical screw-threaded upward extensions jointly forming a stud, said extensions being

- transversely offset from their respective plates, one of them extending through an aperture in the other, abutting fulcrum ribs formed on adjacent faces of said extensions, 5 and a member screwed on said extensions, and a device adapted to be pressed downwardly by said member to press said plates against the wire, said device comprising a ring surrounding said extensions and 10 having a pair of downwardly projecting legs formed with V-notches in their lower ends.
3. A trolley wire support comprising a pair of vertical plates adapted to grip the sides of the wire and formed with semi-cylindrical screw-threaded upward extensions 15 jointly forming a stud, said extensions being transversely offset from their respective plates, one of them extending through an aperture in the other, abutting fulcrum ribs formed on adjacent faces of said extensions, 20 and a member screwed on said extensions, and a device adapted to be pressed downwardly by said member to press said plates against the wire, said device presenting a

V-notch in its lower end in which said plates 25 are adapted to engage.

4. In a trolley wire support, a pair of vertical plates adapted to grip opposite sides of the wire, and having semi-cylindrical upward extensions jointly forming a stud, a 30 barrel screwed on said stud, and a device adapted to be pressed downwardly by said barrel to cause said plates to grip the wire.

5. In a trolley wire support, a pair of vertical plates adapted to grip opposite sides 35 of the wire, and having semi-cylindrical upward extensions jointly forming a stud, a barrel screwed on said stud, and a device adapted to be pressed downwardly by said barrel to cause said plates to grip the wire, 40 said device comprising a ring surrounding said stud below said barrel and having a pair of downwardly projecting legs formed with V-notches in their lower ends.

In testimony whereof I have affixed my 45 signature.

FRANK CHESZNEKY.
